UNITED STATES PATENT OFFICE.

MILLER REESE HUTCHISON, OF BRONXVILLE, NEW YORK.

SIGNALING-HORN, &c.

956,898.

Specification of Letters Patent. Patented May 3, 1910.

Application filed October 2, 1905. Serial No. 280,910.

To all whom it may concern:

Be it known that I, MILLER REESE HUTCHISON, a citizen of the United States, and resident of Bronxville, in the county of Westchester and State of New York, have invented certain new and useful Improvements Relating to Signaling-Horns, &c., of which the following is a specification.

This invention relates to signal horns of the general class employed on automobiles, launches and other vehicles and conveyances, to which class also belong the various devices described in my prior application, Ser. No. 278,562, filed September 15, 1905. In said prior application, I have described various modifications adapted to produce notes or combinations of notes, having any desired degree of musical quality, pleasing to the ear, and capable of use for alarm as well as for amusement. In said prior application, I have also described the particular functional and structural characteristics desirable for producing on the hearer an immediate apprehension of physical harm, such effect being more readily produced by a harsh sound, lacking in musical quality. Many of the devices and expedients set forth in that application will be found useful in connection with my present invention, and any of them may be used in combination with any desired features hereof. Similarly, many of the features of my present invention may be used in connection with the devices of said prior application.

One of the objects of my present invention is, to modify the shape of the horn, so that it may be arranged closely adjacent the body of the conveyance and, at the same time, may be improved for its purpose as a sound projector. To this end, the horn is flattened laterally, so as to have a desired definite relation of vertical and transverse dimensions. When thus constructed and arranged, the sound has less tendency to spread upwardly, where it is lost in the upper air, or downwardly, where it is absorbed, reflected and otherwise broken up or dissipated. At the same time the sound does spread laterally through an arc or zone sufficient for practical purposes. Being to a great extent limited in upward and downward spread, the sound is correspondingly more intense directly in the line of movement and for a reasonable distance on each side of such line.

Another object of my invention, is to simplify the vibrator attachment empl

to excite the air column of the horn. This attachment is usually mounted on the end of the horn, in an exposed position, where it is especially subject to shocks, jars, etc. For some reasons it is sometimes very desirable to eliminate, from such device, all parts which can well be located elsewhere. To this end the means for producing current fluctuations for vibrating the diaphragm are located on the conveyance, and the interrupted or pulsatory current fluctuations are supplied to the electromagnet through suitable circuit connections.

Another object of my invention is, to consolidate and combine the electrical apparatus on automobiles, etc., driven by explosive engines employing sparking mechanism, by utilizing the same battery, and, preferably, the same interrupting means for both sparking coil and horn. This arrangement has many advantages of simplicity, reliability and economy. The horn attachment itself is simplified and the certainty of its operation insured, by reason of the fact that the sparking apparatus, being a vital essential to the operation of the motor, must be always in operative condition, for otherwise the conveyance will not be in motion and will not be in situations where an alarm is necessary. A separate source of energy, either primary or secondary, is also obviated, for the amount of power consumed in working the horn is a negligible draft on the storage batteries ordinarily employed for sparking. Furthermore, where a commutator is used to throw the sparking interrupter out of operation except at the proper instant in the cycle of the operation of the motor, the sounds from the horn are broken up into a succession of sharp, short notes, similar in character to those used on locomotives and steamships to signal immediate, imminent danger. Such a succession of blasts, particularly when of the harsh piercing type previously referred to, is very effective for alarm purposes.

Another object of my invention is, to proportion and adapt the parts and to provide suitable means of escape for water or any foreign substances, such as pebbles, dust, etc. which may find their way through the horn to the vibrating diaphragm.

Another object of my invention is, to provide a special form of vibrating circuit breaker, having an effective length much

greater than the transverse dimensions of the space it occupies. Such a vibrator may be operated from the sparking battery, by being included in a shunt connection around the battery alone, instead of around the battery and its sparking interrupter.

In the accompanying drawings; Figure 1 shows the flattened horn in side elevation and attached electromagnetically operated, diaphragm and casing, in vertical section. Fig. 2 is a diagram of the circuits of the batteries, coil, interrupter, commutator, sparking plugs, etc. combined with and adapted to operate the horn diaphragm. Fig. 3 is an elevation of the horn with attached electromagnetic vibrator, an automobile being shown in dotted lines to illustrate a position in which the horn may be conveniently located. Fig. 4 is a detailed view of an improved form of vibrating circuit breaker which may be used instead of the sparking coil interrupter, and which may be a separate device located in the conveyance, or may be mounted upon and form part of the circuit of the coil shown in Fig. 1. Fig. 5 is a fragmentary detail view in vertical section showing the horn provided with drain holes.

Referring to Figs. 1 and 3, it will be seen that the horn 1 is flattened laterally and is preferably not coiled intermediate of its length, but is formed of substantially straight line elements. The flattening may be such as to make the cross section of the horn an oval, or an ellipse, or, in some cases, the flattening may be carried to the extreme shown in Fig. 1 where the portions 2, 2 are approximately arcs of circles, and the flattened portions 3, are plane surfaces. These plan surfaces may be substantially parallel, or may themselves diverge oppositely, at a suitable, preferably small, angle. In any case, it is preferred that the proportions be so worked out, that the larger vertical diameter of the horn, at the mouth, shall be about 3 or 4 times the transverse diameter. It is obvious that variations in the rate of divergence of the horn are possible without departing from my invention; but in this form it is desirable to avoid the open flaring mouth characteristic of musical horns and ordinary automobile horns, as such form tends to scatter the sound. This flattened horn is of great advantage, especially for automobile purposes, for two reasons, one structural and the other functional. The structural reason is, that the flattening of the horn greatly simplified the difficulties of arranging a long straight horn in a convenient, safe location on the frame of the automobile. This form is peculiarly adapted to be snugly secured, close to the body of the vehicle. The functional advantage as a sounding instrument is, that when so formed, the sound is projected to the greatest

possible extent in the forward direction. There is only a minimum tendency of the sound to spread vertically in useless directions, most of the spreading tendency being lateral. It might be argued that the greatest spread would be in the direction of the longer cross sectional diameter of the horn, but experiment shows the contrary. I consider that this peculiar adaptation of acoustic properties of the flattened horn, to the mechanical conveniences and requirements of use on an automobile or other conveyance, to be a particularly meritorious feature of my invention.

The flattened horn may be provided with any desired form of pneumatic, electromagnetic or mechanical reed or diaphragm vibrator for exciting the air column thereof, but it is preferably provided with a casing mounted upon and forming a closure for the small end of the horn. This casing preferably consists of a cylinder 4, front cap or closure 5, and rear cap or closure 6, the former being provided with a screw-threaded boss, or nipple, 7, for securing it to the horn and the rear cap 6 being provided with suitable binding posts 16, 17, for the circuit connections. Inside of this case, are mounted the diaphragm 8, electromagnet 9, buckling spring 10, and so-called resonant diaphragm 11, all very much as described in my prior application referred to above. The washers 12, 13 and 14 are of any suitable material, preferably non-conducting and water-proof; particularly washer 14 should be waterproof. The magnet 9 is carried by the adjustable bridge piece 15, and may be screwed toward or away from the diaphragm 8, to produce a maximum volume of sound. The so-called resonant diaphragm, or partition, is also adjustable as shown and should be adjusted to such position as would result in the maximum reinforcing or amplifying effect.

As the horn is forwardly directed and preferably straight, and as the protecting screen over the end thereof may be omitted or made very coarse, I have found it desirable to provide the cavity 18, between the diaphragm and the front wall 5 of the case 4, with means for escape of water, dirt, etc. which may, by chance, find their way, through the open end of the horn, to the diaphragm. For this purpose the holes, which I have referred to in my prior application as being sometimes employed in the front wall of the case, may be located at or near the periphery, so as to serve as drains for such space. Preferably there is only one such hole, as at 19, and this is located at the lowermost point. In some cases, as shown in Fig. 1, where it is desired that the air space 18, in front of the diaphragm be inverted, a single opening or passage, at the lowest point of the cavity in front of the dia-

phragm, may, by a passage 20, connect with a closed chamber 21, serving as a trap or drain, in which may collect dust, dirt, water, etc. which may find their way into the diaphragm cavity. This trap may be cleaned from time to time through a suitable removable closure 23. Where it is desired, however, to utilize the opening for the purpose of removing dirt, water, etc., without 5 permitting any accumulation, a directly opening passage 19', as shown in Fig. 5, is preferable. The protecting metallic net 22, over the mouth of the horn, is preferably not entirely dispensed with, but is made 10 of coarse mesh, so as to obstruct the sound as little as possible. It is preferable to regulate the size of mesh, and the space 18, between the diaphragm and the front of the casing, and the outlet at the bottom of such 15 space, whether to the air or into the trap referred to, so that any pebble or similar body, which is capable of passing the mesh of the screen, will also be capable of passing down through the space between the 20 diaphragm and the casing and out through the drain, in the bottom thereof. In any event it is preferable that the exit opening, or drain, be large enough to permit the 25 escape of any foreign body that may be 30 small enough to pass through the rest of the device.

The electromagnetic vibrator is preferably not provided with an interrupter armature within the case 4, the fluctuations or 35 pulsations of currents being controlled elsewhere, preferably by means located at some suitable point upon the automobile.

One very important feature of my invention consists in utilizing the sparking 40 battery and its interrupter as the source of fluctuating or pulsating current for operating the horn. These fluctuations are caused to traverse the electromagnet of the vibrator by suitable serial connection 45 through binding posts, 16, 17. As the coil 9 is preferably of very low resistance, approximately $1\frac{1}{2}$ to 2 ohms, it is quite possible to arrange for throwing the same 50 into circuit in series with the sparking battery, interrupter, coil and commutator. But the extra resistance and impedance on the primary of the coil, resulting from such an arrangement is a disadvantage, and, moreover, the high potential discharge of 55 the primary of the coil serially through the magnet 9 is undesirable. For these and other reasons, the preferred arrangement is, to connect the coil of the electromagnet 9 in a shunt around the sparking coil. In Fig. 60 2, I have shown this arrangement. In said figure, 31 is the battery commonly employed for igniting the motor. As ordinarily arranged, such battery is connected serially through conductors, such as 32, 33, 65 to the shaft of the commutator, diagram-

matically indicated at 34; thence through conducting segment 35, brush contact 36, conductor 37, to the primary 39 of the sparking coil 38, thence through conductor 40 and vibrator 41, carrying armature 42, 70 through adjustable stationary contact 43 and conductor 44 back to the other pole of the battery. Wound upon the core 45 of the induction coil 38, is the secondary, 46, serially connected through 47 and 48 with 75 the sparking plug terminals 49 and 50.

In order to operatively combine my electromagnetically operated horn with such a system, it is only necessary to lead a shunt connection, 51, from the battery binding 80 post or conductor 32, or indeed from any point in conductor 32, 33 or 37, to a binding post, 16 or 17, and then to connect a lead 52 from the other binding post on the horn to the vibrator 41. Obviously, other shunt 85 or serial connections may be used as alternatives, provided, of course, that if the connection be serial, a two-way switch is employed, which will preserve at all times the continuity of the circuit from the battery through 90 the sparking coil, so that the sparking function be not interfered with. Such a shunt is controlled by any suitable form of switch, 53, which may be located on the steering wheel as indicated on Fig. 3, or the control 95 may be from any desired number of points in the vehicle, after the manner fully set forth in my prior application referred to. If desired, the electromagnet 9 may be operated from the battery 31 by a shunt 100 circuit connected across the terminals thereof. In such case, an independent interrupter will be necessary, and in Fig. 4 I have shown a desirable construction for use in such connection. In said figure the electromagnet 60 is provided with a peculiar form of compound vibrator. This vibrator may be used in the manner desired, or, where desired, it may be mounted upon the bridge 15 with its armature in operative 110 relation to the core of the magnet 9 shown in Fig. 1. This compound vibrator consists of a spring 61, suitably supported at 62, and bent or recurved upon itself at 63 and 64. The armature 65 is secured to the free 115 end thereof.

Forward of the bend 63, on the side of said bend away from the support 62, is secured a sparking plate or terminal 66, adapted to contact with stationary screw 67 120 rigidly held by, but adjustable in, the fixed support 68. The magnet coil 60 is connected in series through this contact, so that the circuit is made and broken with each vibration of the armature. The location of this 125 contact maker is preferably that shown, though it may be anywhere between the two points 63 and 64.

The free end of the vibrator which carries the armature is preferably provided with 130

some kind of a link connection, freely or slidably engaging the adjacent reverse portion of the spring, and provided with a shoulder, or stop of some kind, adapted to engage said spring, and suddenly and sharply move the same toward the core of the magnet, and thereby break the circuit at 66. Such a connection is operatively indicated in the drawing as consisting of a screw 69, threaded into the armature 63, and adjustable therein, its position being insured by screwing up the locknut 70. The head 71 of the screw 69 serves as the shoulder for engaging the intermediate section 15 of the vibrator, for effecting the sudden break above referred to. Any equivalent loose connection, provided with a stop to effect the sudden break, may be employed. Furthermore, the proportion of parts and 20 the normal clearance between the armature and the core of the magnet are capable of great variation. It will be obvious that, by this arrangement, I am able to get a great effective length of spring in a comparatively 25 small compass, so that I may have a vibrator capable, for instance, of being inclosed in the case 4, and yet which will have an effective length practically equal to twice the diameter of such a case.

30 In operation, the armature 63 is drawn toward the core when the latter is energized, with a rapidly accelerating motion, and, at just the proper point when such movement is most rapid, the shoulder 71 will engage 35 the intermediate length of spring and break the circuit at 66 with the movement equivalent to a hammer blow; thus effecting an extremely sudden rupture of the circuit, and a correspondingly sharp kick of the coil.

40 While I have described the various features of my invention with great particularity, it is obvious that many equivalents of the various devices and their arrangements are possible, and I do not intend to 45 limit my claims except as therein specified.

What I claim is:

1. In an automobile provided with an explosive motor, igniting apparatus, battery and circuit breaker, an alarm comprising a laterally flattened horn adjacent the side of said automobile, electromagnetic means exciting said horn, and a circuit therefor connected in series with the circuit breaker of said igniting apparatus and in parallel with 55 the primary of the spark coil thereof.
2. An automobile, explosive motor and igniting apparatus therefor including a battery, interrupter and coil, in combination with a laterally flattened horn secured adjacent a side of said automobile, electromagnetically controlled means for exciting said horn and a circuit therefor connected in parallel with said coil.
3. A conveyance, explosive motor and igniting apparatus therefor, including a bat-

tery and circuit breaker, in combination with a horn mounted upon said conveyance, electromagnetically controlled means for exciting said horn and a circuit therefor connected in series with said battery and circuit breaker, and in parallel with the sparking coil of said igniting apparatus.

4. A conveyance, explosive motor and igniting apparatus therefor, including a battery, interrupter and coil, in combination with a horn mounted upon said conveyance, electromagnetically controlled means for exciting said horn and a circuit therefor connected in parallel with said coil.

5. A conveyance, explosive motor and electric igniting apparatus therefor including a battery, interrupter, and commutator coil in combination with a horn mounted upon said conveyance, electromagnetically operated means for exciting said horn and a circuit therefor connected in parallel with said coil and in series with said battery, interrupter and commutator.

6. A conveyance, explosive motor and igniting apparatus therefor, including a battery, interrupter, coil and commutator in combination with a horn, electromagnetically operated means for exciting said horn and a circuit therefor connected in series with said battery commutator and circuit breaker.

7. A conveyance, an explosive motor and an igniting apparatus including a circuit therefor, a source of energy therein and means for producing intermittent trains or 100 groups of rapidly recurring variations of the current from said source in combination with an electromagnetic horn energized from said circuit and sounding in synchronism with the flow of current therethrough.

8. An automobile, explosive motor and igniting apparatus therefor, including a battery and a circuit breaker, in combination with a laterally flattened horn secured adjacent to a side of said automobile, an electromagnet and diaphragm for exciting said horn and a circuit therefor, connected in series with the battery and circuit breaker, and in parallel with the sparking coil of said igniting apparatus.

9. An automobile, explosive motor and igniting apparatus therefor including a battery, interrupter and coil, in combination with a laterally flattened horn secured adjacent a side of said automobile, an electromagnet and diaphragm for exciting said horn and a circuit therefor in parallel with said coil.

10. A conveyance, explosive motor and igniting apparatus therefor, including a battery and circuit breaker, in combination with a horn mounted upon said conveyance, an electromagnet and diaphragm for exciting said horn and a circuit therefor connected in series with said battery and circuit breaker.

- breaker, and in parallel with the sparking coil of said igniting apparatus.
11. A conveyance, explosive motor and igniting apparatus therefor, including a battery, interrupter and coil, in combination with a horn mounted upon said conveyance, an electromagnet and diaphragm for exciting said horn and a circuit therefor connected in parallel with said coil.
12. A conveyance, explosive motor and electric igniting apparatus therefor including a battery, interrupter, commutator and coil, in connection with a horn mounted upon said conveyance, an electromagnet and diaphragm, for exciting said horn and a circuit therefor connected in parallel with said coil and in series with said battery, interrupter and commutator.
13. A conveyance, explosive motor and igniting apparatus therefor, including a battery, circuit breaker, coil and commutator in combination with a horn, electromagnet and diaphragm for exciting said horn, and a circuit therefor connected in series with said battery and circuit breaker, and in parallel with the sparking coil of said igniting apparatus.
14. A conveyance, an explosive motor, an igniting apparatus therefor and a source of varying electric currents in series with said igniting apparatus, in combination with an electromagnet, diaphragm and horn, and means for serially connecting the electromagnet with said source of varying electric currents.
15. In an alarm for conveyances, a horn adapted to be mounted in a forwardly directed position, a casing mounted on the rear and smaller end of the horn, a diaphragm spanning said casing and spaced away from the rear end of the horn and means for removing matter entering the forward end of the horn and passing to the space in front of the diaphragm.
16. In an alarm for conveyances, a horn adapted to be mounted in a forwardly directed position, diaphragm-sound producing means at its rear and smaller end and a casing inclosing said rear end and said diaphragm, said casing being provided in a forward wall with an orifice communicating with the space in front of the diaphragm.
17. In a conveyance, a forwardly directed horn and a diaphragm closure and casing mounted on its rear and smaller end, said casing having a vertical wall on its fore end provided with a drain orifice.
18. In a conveyance, a forwardly directed horn, a diaphragm and casing closure mounted on its rear and smaller end, said casing being provided with a drain orifice and a discharge chamber for said orifice.
19. In a conveyance, a forwardly directed horn, a diaphragm containing casing mounted on the rear and smaller end of the horn, said casing being provided with a drain orifice, and a removable closure for the drain orifice.
20. In a conveyance, a forwardly directed, substantially straight horn, and a diaphragm and casing closure mounted on the rear and smaller end of the horn, said casing being provided with an orifice for the discharge of matters entering the front end of said horn.
21. In a conveyance, a forwardly directed, substantially straight horn, a diaphragm and casing closure mounted on the rear and smaller end of the horn, said casing being provided with a drain opening, and a closed discharge chamber for said drain opening.
22. A vibratory acoustic diaphragm and a case secured over the front of said diaphragm and formed with an opening or passage for propagation of sound to the outer air, the space in front of the diaphragm between it and the case being provided adjacent the periphery of the diaphragm with an opening or passage for escape of water, dust, and solid particles.
23. A vibratory acoustic diaphragm and a case secured over the front of said diaphragm and formed with an opening or passage for propagation of sound to the outer air, the space in front of the diaphragm between it and the case being provided adjacent the periphery of the diaphragm with an opening or passage for escape of water, dust, and solid particles, together with a closed trap or chamber below said opening.
24. An acoustic vibratory member, a resonator therefor, and an enlarged chamber adjacent said vibratory member and between it and said resonator, said chamber being provided with a small opening for the escape of water, dust, and particles.
25. In a conveyance, a forwardly directed horn, a diaphragm secured to the rear end of said horn by a case having a front wall approximately parallel with said diaphragm, said parts being formed with an opening adjacent the periphery of the diaphragm for the escape of water, dust, and solid particles.
26. An alarm or signaling device adapted for use in exposed situations, comprising a horn having a diaphragm mounted at its smaller end and an inclosing casing for said diaphragm and smaller end, said casing being provided with a discharge orifice communicating with the space before the diaphragm.
27. An alarm or signaling device adapted for use in exposed situations, comprising a substantially straight horn, and a diaphragm closure and casing mounted on its smaller end, said casing being provided with a discharge opening.
28. An alarm or signaling device adapted for use in exposed situations comprising a straight tube or horn having slightly diverging side walls and of flattened cross-

- section, a casing of larger dimensions than the smaller end of the horn mounted on such smaller end, and a diaphragm and means for vibrating the same within said casing, 5 said casing being provided with a discharge orifice in a front wall in line with a major axis of said horn, said orifice communicating with the space between the diaphragm and the said front wall of the casing.
- 10 29. In a conveyance, a substantially straight, forwardly directed horn, a diaphragm and case at the rear end of said horn, forming an airtight closure therefor, said case being provided with a drain opening leading therefrom and an air-tight chamber serving as a discharge chamber and closure for said drain.
30. In a conveyance, a vertically deep and laterally shallow horn having a forwardly directed mouth, corresponding sides of said horn diverging symmetrically, a closed casing inclosing the rear end of said horn, a sealing diaphragm spanning the casing behind the rear end of the horn, and 15 electromagnetic means for actuating said diaphragm located within the casing, said

diaphragm being located somewhat behind the rear end of the horn and the front wall of the casing and said casing being provided with an orifice for the discharge of foreign matter communicating with the chamber thus formed.

31. In a conveyance, a forwardly directed horn, a casing inclosing the rear end of said horn and of somewhat greater diameter, an imperforate diaphragm within and spanning the chamber of the casing and spaced back of its forward wall and means for actuating said diaphragm to emit loud sounds and vibrate forcibly, said casing being provided with a discharge orifice for foreign matter communicating with the space between said diaphragm and the forward wall of the casing.

Signed at New York city, in the county of New York, and State of New York this 29th day of September A. D. 1905.

MILLER REESE HUTCHISON.
